UNITED STATES PATENT OFFICE.

HARRY W. DYER, OF EAST ORANGE, NEW JERSEY, ASSIGNOR TO THE DYER REVOLVING DOOR COMPANY, A CORPORATION OF ARIZONA TERRITORY.

REVOLVING DOOR.

No. 886,317.

Specification of Letters Patent.

Patented April 28, 1908.

Application filed August 30, 1907. Serial No. 390,713.

To all whom it may concern:

Be it known that I, HARRY W. DYER, a citizen of the United States, residing at East Orange, in the county of Essex and State of New Jersey, have invented certain new and useful Improvements in Revolving Doors, of which the following is a full, clear, and exact description.

My invention relates to revolving doors of the type in which the door comprises a plurality of wings extending radially or substantially so, and in which one or more of the wings are hinged with respect to each other, so that they may be folded, thus affording a free passageway whenever desired, and in which the door when folded may be moved to one side of the passage if desired, so as to leave the same entirely free for substantially its entire width.

My invention has for its object the provision of improved means for bracing the movable wings and for locking the same when open and when in folded position; also improved means for locking the door in the position which it occupies when acting as a revolving door; also improved means for rotatably supporting the door and for carrying the door from its normal or rotary position to one side so as to leave the passageway free; also the provision of means for moving the said door from its normal position to one in which the passageway is substantially unobstructed; and finally the provision of improved details of construction, as hereinafter set forth and claimed.

Reference is hereby made to the accompanying drawings of which,

Figure 1 is a section on line 1—1 of Fig. 2; Fig. 2 is a front elevation partly in section showing a door constructed in accordance with my invention, and showing in section the adjacent parts of the structure of the building to which the door is applied; Fig. 3 is an enlarged section on the line 3—3 of Fig. 4; Fig. 4 is an enlarged section on line 4—4 of Fig. 2; Fig. 5 is a detail front view of the lock for holding the sections of the central rod of the door in raised or lowered position; Fig. 6 is a section on line 6—6 of Fig. 5; Fig. 7 is a detail section showing one of the edges of the door with the weather strip applied; Fig. 8 is a detail sectional view of the lower end of the central rod and its supporting shoe; Fig. 9 is a detail section of the upper or lower edge of one of the wings of the door showing the

weather strip; Fig. 10 is a plan view of the turn table from which the door is suspended; Figs. 11 and 12 are detail views showing the mechanism for locking one of the hinged wings of the door in its open and closed positions, and Fig. 13 is an elevation showing the mechanism for operating the turn table for moving the door from its central or rotary position to one side of the passageway.

In all the views corresponding parts are designated by the same reference characters.

The door shown comprises a support or body 1, formed with a pair of oppositely disposed wings H, and rotatably supported by a central axis in the form of a sectional tube V. Within the body 1 of the door is a block H², preferably of metal, formed in two parts, as shown in Fig. 3. These blocks H² carry the entire weight of the door, and apply the same to the block W, which forms a part of the roller bearing E², carried by the turn table, the weight being transmitted through the sectional tube V, the upper member V¹ of which is threaded within the bearing block W, and the upper block H². The intermediate member V² is threaded within and connects the upper and lower blocks H², and the lower member V³ is threaded within the lower block H². It will be thus seen that the entire weight of the door is carried by the blocks H² and tubing V, by which the weight is applied to the ball bearing. The body of the door therefore rotates freely about its axis which is held in its normal position by a sectional rod U. The sections of the said rod are vertically movable, and means are provided for raising and lowering the said sections when desired and for locking the same in either position. In the position shown in Fig. 3, the upper section is in its elevated position, the upper end occupying a socket in the block T, and the lower section is in its depressed position, so that the end of the shoe X engages a socket in the block Y, which is sunk in the floor. The shoe X is a tube within which the lower end of the rod U is threaded. The bottom of the shoe is closed and formed with a stud for engaging the socket of the block Y. The door therefore cannot be moved from its normal or rotary position, unless the sections of the rod U be moved longitudinally so as to withdraw the ends of the same from the blocks T and Y respectively. The means for accomplishing this

result is illustrated in Figs. 3, 4 5 and 6. A recess 2 is formed within the body 1 and a similar, but narrower recess 3, is formed within the block H². These recesses as will 5 be seen are closed when the hinged wing is open or in radial position, so that there is no access thereto at such time, but the movement of the wing upon its hinge, exposes the said slot so that it then becomes possible to 10 raise and lower the upper and lower sections of the rod U. Within each of said sections is set a piece 4, which extends through the slots 2 and 3. The outer end of said piece 4 is forked, and within the same a lever D² is 15 hinged by a knuckle joint, so that when in its vertical position it occupies the slot 2 and lies entirely within the body 1 of the door. In the position shown in full lines in Fig. 6, the lower end of the member D² rests upon 20 the bottom of the slot 2, and thereby supports the rod U. When the lever D² is brought out into a horizontal position, it serves as a handle for lifting the section U, and when in its elevated position, (shown in 25 dotted lines) it holds the rod U in an elevated position by reason of the lower end of the member D² resting upon shoulders 5, 5, formed in the side walls of the slot 2. The construction of the device C² for raising and 30 lowering the upper section of the rod U is identical with the structure which has been described for the operation of the lower section of the said rod.

The hinged wings H which are adapted to 35 be folded with respect to the body of the door are carried by the hinges B², and are normally held in radial position by means of the hinged braces B. They are locked in this 40 position by the following means: The fixed wing H carries a piece D, having an outwardly projecting arm to the end of which is pivoted a hollow or tubular member C, and within the same is telescoped a rod C², one end of which is pivoted to a piece F², secured 45 to the hinged wing H. When the hinged wing is in the position shown in full lines in Fig. 4, the rod C² is almost entirely within the tube C, and in this position the detent 6 of a locking latch K² (Figs. 11 and 12) which is 50 hinged upon the tube C, engages a recess 7, formed in the rod C², thus preventing the rod from moving longitudinally with respect to the tube C. Upon the movement of the latch K², as indicated in dotted lines in Fig. 55 11, the detent 6 is withdrawn from the recess 7, and the wing H can be moved upon its hinge into the position indicated in dotted lines in Fig. 4. This movement causes the rod C² to move longitudinally with respect to 60 the tube C, and when the position shown in dotted lines is reached, a second recess similar to the recess 7, and which is formed in the rod C², comes opposite the detent 6 of the latch K², which may be moved so as to engage 65 said recess, thereby locking the hinged

wing H firmly in its folded position. The door is then in suitable form for being moved bodily or translated to one side so as to leave a free passageway. This is accomplished after withdrawing the ends of the sectional rod U from their sockets, by a rotation of the turn table before referred to. This turn table is preferably seated above the ceiling over the door, and comprises a base O, supporting a circular track P, shown as a channel, a spider R, upon the ends of whose radial arms are mounted rollers Q which rest upon the track P, and a disk N, which is firmly secured to the spider R by the straps S, so as to turn with said spider. The tube V passes through an opening in said disk N and the latter being concentric with the track P, at all times closes the circular opening formed in the ceiling above the door for the passage of said tube V. One of the radial arms of the spider R is enlarged to form the cup of the roller bearing E², which supports the tube V, which carries the revolving door.

It is obvious that if desired the turn table may be caused to rotate by merely pushing the door from the position indicated in full lines in Fig. 1 to that indicated in dotted lines, whereby the door describes a circular path, and this is usually the way in which the device will be operated, but in some instances, as, for example, where very heavy metallic doors are used, it will be desirable to provide mechanism for causing a rotation of the turn table, and thereby producing the desired movement of the door. Such means 100 may be of any type or form whatever, either electrical, pneumatic, mechanical, etc., but I have shown for this purpose a mechanical movement comprising a circular rack 8, applied to the spider R, with which engages a 105 pinion 9, carried on the end of a horizontal shaft 10, the other end of said shaft being provided with a sprocket 11, over which passes a chain 12, said chain also passing over a sprocket 13, carried by horizontal shaft 14, which may be operated by a crank 110 15. When the door is in its folded position at one side of the passageway, it may be locked by means of vertical bolts L, applied to the top and bottom edges thereof (see Fig. 115 2), said bolts engaging suitably located sockets in the floor and ceiling, and being controlled by locks L. The same bolts are also useful for holding the door while in its normal or rotary position, so that it will completely close the passageway, and will prevent any unauthorized person from entering the building, as, for example, when it is desired to close the building at night. All that is necessary is to provide suitable sockets in 120 the floor in the proper positions to cause the door to completely close the passageway, as when turned through an angle of 90 degrees from the position shown in full lines Fig. 1.

The use of a turn table for imparting a 130

movement of translation to the folded door is advantageous in that it permits the ceiling to be practically without any opening, since the disk N fits closely, and there is only sufficient space around its periphery to permit it to rotate freely. Another advantage is that the translating movement may be effected by pushing against the edge of the folded door in the direction of its width, thereby concentrating one's weight upon the door, so that one man can move a heavy door, which he might not be able to do by pushing against the face of the door, since in this case he could not concentrate his weight at one point, because the door would tend to rotate and pressure would have to be applied at points on opposite sides of its center. A further advantage resides in the fact that the frictional resistance of the translating device against movement may be reduced to a minimum.

What I claim, is:

1. The combination of a turntable support, a turntable carried thereby and having at least three points of support spaced around its circumference, a roller at each point of support, a door comprising radial wings, and means for rotatably supporting said door upon said turntable at a point eccentric thereto and at a distance from the center thereof which does not exceed the distance of one of the supporting rollers from said center.

2. The combination of a turntable support, a turntable carried thereby and having at least three points of support spaced around its circumference, a roller at each point of support, a door comprising radial wings foldable with respect to each other, and means for rotatably supporting said door upon said turntable at a point eccentric thereto and at a distance from the center thereof which does not exceed the distance of one of the supporting rollers from said center.

3. A revolving door comprising radial wings and a support therefor, a translating device, a rotary bearing carried by said translating device, a vertical tube supported by said bearing, depending therefrom and carrying said support, means for locking said translating device comprising a rod sleeved within said tube and extending through the rotary bearing which supports said tube and of sufficient size to fill the bore thereof, a fixed socket above said bearing and adapted to directly receive the upper end of said rod, and means for sustaining said rod in an elevated position, said means permitting the rod to be lowered so as to be withdrawn from said socket.

4. A revolving door comprising radial wings, a translating device, means for rotatably supporting said door upon said translating device, and supporting means for said translating device which permits movement

thereof in a circular path, the diameter of which does not exceed the radius of the door.

5. A revolving door comprising radial wings, a turntable, and a rotary support for said door carried by said turntable at such a distance from its axis that the diameter of the path of said rotary support does not exceed the radius of the door.

6. A revolving door comprising a body and a folding wing, said body being formed with a recess which is closed by said wing when in an open position, a lateral shoulder in said recess, a vertically movable rod inclosed within said body and accessible through said recess, a handle for operating said rod, said handle being movable on a horizontal pivot into and out of said recess and being adapted to rest upon said shoulder to hold said rod in an elevated position.

7. A revolving door comprising a body and a folding wing, said body being formed with a recess having a lateral shoulder, a vertically movable rod inclosed within said body and accessible through said recess, an arm D² secured to said rod by a knuckle joint and movable on a horizontal pivot into and out of said recess, said arm having a lateral extension adapted to rest upon said shoulder to hold said rod in an elevated position.

8. A revolving door comprising radial wings, a translating device movable in a curvilinear closed path, means for rotatably supporting said door upon said translating device, and means distinct from said door and applied to said translating device for moving it around its closed path, whereby a continuous movement of the translating device carries the door from a central supporting point to one side and then back to the starting point.

9. A revolving door comprising radial wings, a rotary translating device capable of one or more complete revolutions, means for rotatably supporting said door upon said translating device at a point eccentric thereto, and means distinct from said door and applied to said translating device for imparting continuous rotary movement thereto.

10. A revolving door comprising radial wings, a translating device, means for rotatably supporting said door upon said translating device, comprising a vertical tube, and means for centering said tube comprising a rod sleeved within said tube and a hollow shoe closely surrounding the lower end of said tube, said rod being secured to the interior of said shoe.

11. A revolving door comprising radial wings, a turn table, means for rotatably supporting said door upon said turn table at a point eccentric thereto, and a circular member concentrically carried by said turn table and whose radius is not less than the distance from the body support to the center of the turn table, whereby it is adapted to close

- the opening in the ceiling of the doorway to which the door is applied.
12. The combination of a doorway having an apertured ceiling, a revolving door mounted in said doorway below the ceiling and comprising a body and a folding wing, a rotary translating device above the ceiling, means passing through the aperture of the ceiling for rotatably supporting said body upon said translating device, and a circular member movable with said translating device and closing the aperture in said ceiling.
13. A doorway comprising side frames and upper and lower horizontal plane surfaces, in combination with a revolving door mounted in said doorway, a rotary translating device beyond the vertical limits of said doorway, an aperture in one of the horizontal surfaces of the doorway, a support carried by said translating device passing through said aperture and sustaining said door, and a circular member movable with said translating device and closing the aperture in said horizontal surface.
- 25 14. A revolving door comprising a body and radial wings, a translating device, means for rotatably supporting said door upon said translating device comprising vertical tube sections supported by and depending from the translating device and connected by a block H^2 of larger cross-section secured to said sections, and a post or body 1 having a recess within which said block is embedded and which it engages to support the door.
15. A revolving door comprising a body 35 and radial wings, a translating device, means for rotatably supporting said body upon said translating device comprising a vertical tube supported by and depending from the translating device, a block rigid with and of larger 40 cross-section than said tube, the body of the door being formed with a recess within which said block is embedded and which it engages to support the door, a vertically movable locking rod within said tube and block and 45 said block being formed with a slot extending therethrough to give access to said rod.
16. A revolving door comprising radial wings, a bearing upon which said door is rotatably mounted, said bearing being movable in a substantially horizontal path forming a complete circle, and means movable with said bearing in a plane between the door and its bearing to maintain a barrier therebetween.
- 55 17. The combination with a turntable, of a revolving door, a bearing on which said door is mounted to turn, the said bearing being connected to and movable with said turntable around a complete circle, and means on said turntable for closing the end of the cylinder described by the path of movement of the axis of said door.

HARRY W. DYER.
